United States Patent Office

Des. 188,147
Patented June 7, 1960

188,147

ANCHOR BOOM

Fred C. Good, 521 W. Glenwood Ave., Philadelphia, Pa.

Filed Aug. 5, 1959, Ser. No. 57,076

Term of patent 7 years

(Cl. D71—1)

Figure 1 is a perspective view of an anchor boom embodying my new design, the side not disclosed being substantially the same as that shown;

Fig. 3 is a sectional view taken on the lines 3—3 of Fig. 2.

I claim:

The ornamental design for an anchor boom, as shown and described.
